COMBINED TOILET SEAT AND COVER

Luigi Colani, Sassenberg, Germany, assignor to Dansk
Pressalit A/S, Aarhus, Denmark

Filed Jan. 10, 1975, Ser. No. 540,201

Claims priority, application Denmark Dec. 18, 1974

Term of patent 14 years

Int. Cl. D23—02

U.S. Cl. D23—71

FIG. 1

FIG. 2

FIG. 3

FIG. 4

FIG. 5

FIG. 6

FIG. 7

FIG. 8

FIG. 9

FIG. 10

FIG. 1 is a front perspective view of a combined toilet seat and cover showing my new design;

FIG. 2 is a side perspective view thereof, showing the cover in the closed position;

FIG. 3 is a front perspective view of the seat portion thereof;

FIG. 4 is a rear perspective view of FIG. 3;

FIG. 5 is a side perspective view of FIG. 3;

FIG. 6 is a bottom perspective view of FIG. 3;

FIG. 7 is a front perspective view of the cover portion thereof;

FIG. 8 is a rear perspective view of FIG. 7;

FIG. 9 is a side perspective view of FIG. 7; and

FIG. 10 is a bottom perspective view of FIG. 7.

I claim:

The ornamental design for a combined toilet seat and cover, substantially as shown.
